BASE FOR POST TOP OUTDOOR LUMINAIRES

Bernard R. Stockwell, Sunbury, Ohio, assignor to Holophane Company, Inc., New York, N.Y., a corporation of Delaware

Original design application Nov. 9, 1966, Ser. No. 4,591, now Patent No. 209,465, dated Dec. 5, 1967. Divided and this application June 28, 1967, Ser. No. 8,204

Term of patent 14 years

(Cl. D48—31)

FIG. 1 is a front elevational view of the first embodiment of my new design for the base for post top outdoor luminaires, the luminaires and fragmentary post being shown in broken lines for illustrative purposes only;

FIG. 2 is a top plan view of the embodiment of FIG. 1;

FIG. 3 is a right-side sectional view taken along line 3—3 of FIG. 2, the left-side being the same in appearance;

FIG. 4 is a partial rear elevational view of the embodiment of FIG. 1;

FIG. 5 is a top plan view of a second embodiment of the base with the luminaires shown in broken lines for illustrative purposes only;

FIG. 6 is a sectional view of the embodiment of FIG. 5 taken along line 6—6 of FIG. 5;

FIG. 7 is a right-side sectional view taken along line 7—7 of FIG. 5;

FIG. 8 is a sectional view taken along line 8—8 of FIG. 5;

FIG. 9 is an elevational view of a third embodiment of the base with the luminaires and fragmentary post shown in broken lines for illustrative purposes only, and with the support arms partially shown for convenience of illustration;

FIG. 10 is a top plan view of the embodiment of FIG. 9;

FIG. 11 is a right side elevational view of the embodiment of FIG. 9 with the support arms partially shown for convenience of illustration, the left-side view being the same in appearance; and

FIG. 12 is a rear elevational view of the embodiment of FIG. 9 with the support arms partially shown for convenience of illustration.

The dominant features of my design reside in the portions shown in full lines.

This is a division of Design application Ser. No. D-4,591, filed Nov. 9, 1966, entitled "Base for Post Top Outdoor Luminaires," now Patent No. D-209,465, granted Dec. 5, 1967.

I claim:

The ornamental design for a base for post top outdoor luminaires, substantially as shown and described.
